UNITED STATES PATENT OFFICE.

JOHN F. MEIGS AND HERMAN G. JAKOBSSON, OF SOUTH BETHLEHEM, PENNSYLVANIA,
ASSIGNORS TO BETHLEHEM STEEL COMPANY, OF SOUTH BETHLEHEM, PENNSYLVANIA,
A CORPORATION OF PENNSYLVANIA.

GUN-SIGHT.

No. 895,482.

Specification of Letters Patent. Patented Aug. 11, 1908.

Application filed June 18, 1907. Serial No. 379,664.

To all whom it may concern:

Be it known that we, JOHN F. MEIGS and HERMAN G. JAKOBSSON, a citizen of the United States and a subject to the King of Sweden, respectively, and residents of South Bethlehem, county of Northampton, and State of Pennsylvania, have invented certain new and useful Improvements in Gun-Sights, of which the following is a specification.

The present invention relates to improvements in gun sight mountings, and will be described in connection with the accompanying drawings, in which—

15 Figure 1 is a side elevation of a sight constructed and mounted in accordance with the present invention; Fig. 2 is an end elevation of the sight, partly in section; Fig. 3 is an elevation, a plate or side of the casing being removed; Fig. 4 is a sectional view, on an enlarged scale, through a slightly different form of telescope from that shown in Figs. 1 to 3, and Fig. 5 is an end view of said telescope.

25 The casing A is so formed as to provide a chamber in which the main adjusting parts of the device may be concealed by means of a removable cap-piece 2, and said casing is provided with a flange or extension which 30 may be bolted by means of bolts 1, or otherwise, to any suitable part of the gun or the gun mount. In bearings in the casing turns a stud C upon which is an eccentric 3 receiving a strap 4 from which extends a rod or 35 arm D, the latter projecting upward through a block or cylinder B, the reduced ends of which turn in bearings of the casing and its cap, and which block B is slotted to receive the end of the rod D, the latter, as shown, 40 projecting upward and supporting any suitable telescope or sighting device G.

To the outer end of the stud C is secured a blade or arm F and is provided with suitable means for turning the stud as a knob 5, the 45 axis of which is concentric with that of the stud, the said blade being movable over a curved and graduated extension 6 of the cap piece, and the blade having a beveled edge α at the point where the blade crosses the 50 graduated portion of the plate 6. The end of the blade F is provided with a clamping device F² by means of which the blade F may be clamped in any desired radial position upon the plate 6. The eccentricity of the

stud C must have such a relation to the distance between the axes of the stud and of the rocking block B that in carrying the blade F over the entire scale on the plate 6 to an extent corresponding in this case to 200° a rocking movement of 20°, or the full elevation of the gun, will be imparted to the block B and the telescope G.

As above described, the apparatus is used by releasing the clamp F² and swinging the blade or lever F by turning the knob 5 until it registers the desired range on the graduation on the plate 6. As this movement is effected, the eccentric upon the stud C, turning with the knob, oscillates the rod D and the telescope G. Any deflection of the sight line 70 may be had by mounting the telescope so that it may move laterally upon the rod D by means of a screw K, the extent of shifting movement being indicated by a scale w upon the screw in its relation to a point 9 upon the frame of the telescope. Preferably, however, the sighting arrangement shown in Fig. 4 is used consisting of a metallic tube 10 having a guide at the rear end for a dovetailed perforated slide 12, with a projection 80 13 adapted to engage a screw 14, which may be turned by means of a hand knob 15. By turning the knob the slide may be carried to one side or the other to vary the position of the perforation v in respect to the cross hairs 18. 85

For fort and naval guns, no levels are required, but for field or mountain guns a transverse level J is fixedly secured to the frame A to indicate the adjustment of the carriage transversely on its wheels; a level 90 M extending fore and aft is arranged at the side of the telescope to accompany the movements of the latter and indicate any change from horizontal.

By the above arrangement the parts may 95 be positioned with great rapidity, thus saving much of the time heretofore required in laying off the range; there is no lost motion or back lash, as there are no gears, while the parts may be readily manufactured and accurately fitted with a comparatively small amount of machining, and without hand labor, and further, the device is strong and compact, as the working parts are inclosed in a practically air tight compartment, and 100 free from dust and the admission of moisture.

It is not essential to mount the telescope directly upon the rod D, as the latter may be

shortened so as simply to play in the rocking block B, while the frame of the telescope may be bolted directly to the latter so as to have only an oscillating movement, and no up and down movement, as in the case of the construction shown.

While we have shown and described an eccentric upon the stud, and a strap encircling the eccentric and connected with the bar D, it will be evident that an equivalent construction would be a crank shaft, the wrist pin of which enters an opening in the bar, or plays in the slot in the bar connected to the rocking block.

Without limiting ourselves to the precise construction and arrangement of parts shown we claim:

1. The above described gun sight mounting consisting of a casing inclosing a chamber, a stud extending through said chamber and provided within the same with an eccentric, and with external means for turning the stud, a strap encircling the eccentric and connected with an arm, a rocking block mounted to rock in the casing and perforated for the reception of the said arm, and a telescope mounted upon the outer end of said arm.

2. The combination of a hollow casing, its rocking block, provided with a slot, a stud extending through the casing and provided with an eccentric therein, a strap encircling the eccentric, and an arm connected with the strap and extending into the slot in the block, and a telescope mounted to rock with the block, as set forth.

3. The combination of the casing a stud extending into and from the same and provided with an eccentric within the casing and with means for turning it from the outside of the casing, a strap encircling the eccentric, a bar connected to the strap, a rocking block

slotted to receive said bar, and a telescope connected to rock with the block.

4. The combination of a casing, a stud extending into and from the casing and provided with means exterior to the casing for turning the stud, a rocking block, a bar extending therefrom, and means for oscillating said bar by the turning of the stud, a telescope supported to rock with the block, an arm or blade extending from the stud, and a scale upon the casing over which said arm travels.

5. The combination of a casing, a stud extending into and from the casing and provided with means exterior to the casing for turning the stud, a rocking block, a bar extending therefrom, and means for oscillating said bar by the turning of the stud, a telescope supported to rock with the block, an arm or blade extending from the stud, a scale upon the casing over which said arm travels, and means for clamping the arm in any position to which it may be adjusted.

6. A casing consisting of the recessed part A, a cap for closing said recess, combined with a stud extending through the casing and having a knob at the outer end, a graduated scale upon the casing, and an arm extending from the stud over said scale, a rocking block at the top of the casing, a bar extending from the said block downward, and means for swinging said bar by the rotation of the stud, and a telescope supported to rock with the block.

In testimony whereof we affix our signatures in presence of two witnesses.

JOHN F. MEIGS.
HERMAN G. JAKOBSSON.
